MICROSCOPE STAND

Paul A. Hoogesteger, Brighton, and Jacob W. Patla, Rochester, N.Y., assignors to Bausch & Lomb Incorporated, Rochester, N.Y., a corporation of New York

Filed Oct. 3, 1966, Ser. No. 4,135

Term of patent 14 years

(Cl. D57—1)

FIG. 1

FIG. 2

FIG. 1 is a front perspective view of a microscope stand, taken from one side, showing our new design; and FIG. 2 is a rear perspective view taken from the other side of said stand.

The design is substantially symmetrical in form with the obscured side in each view being substantially similar to the exposed side.

The broken lines are shown for illustrative purposes only.

We claim:

The ornamental design for a microscope stand, substantially as shown and described.
